TAPE CONTROL UNIT FOR AN AUTOMATIC SORTER OR THE LIKE

George D. Del Vecchio, North Rose, N.Y., assignor to
Xerox Corporation, Rochester, N.Y., a corporation of
New York

Filed Aug. 2, 1967, Ser. No. 8,099

Term of patent 14 years

(Cl. D26—5)

FIG. 1

FIG. 2

FIG. 5

FIG. 6

FIG. 3

FIG. 4

FIG. 1 is a front perspective view of a tape control unit for an automatic sorter or the like showing my new design;

FIG. 2 is a front elevational view thereof;

FIG. 3 is an elevational view taken from the left side thereof;

FIG. 4 is an elevational view taken from the right side thereof;

FIG. 5 is a top plan view thereof; and

FIG. 6 is a rear elevational view thereof.

The broken line representation of a control tape in FIGS. 2 and 4 is for purposes of illustration only.

I claim:

The ornamental design for a tape control unit for an automatic sorter or the like, as shown and described.
